TRANSPONDER

Edward J. King, Jr., Shawnee Mission, and Bennett J. Copeland, Overland Park, Kans., assignors to King Radio Corporation, a corporation of Kansas

Filed Sept. 26, 1968, Ser. No. 13,732

Term of patent 14 years

Int. Cl. D14—03

U.S. Cl. D26—14

Fig. 1.

Fig. 2.

FIG. 1 is a front view of a transponder showing our new design; and

FIG. 2 is a perspective view of our transponder.

The characteristic features of the design reside in the full line portions.

The conventional numerals disclosed in broken lines are shown for illustrative purposes only.

We claim:

The ornamental design for a transponder, as shown and described.
